UNITED STATES PATENT OFFICE.

JOHN OSCAR WEISSE, OF LA CROSSE, WISCONSIN.

INCLOSURE FOR PORCHES.

1,296,243.

Specification of Letters Patent.

Patented Mar. 4, 1919.

Application filed June 19, 1918. Serial No. 240,813.

To all whom it may concern:

Be it known that I, JOHN OSCAR WEISSE, a citizen of the United States, residing at La Crosse, in the county of La Crosse and 5 State of Wisconsin, have invented a new and useful Inclosure for Porches, of which the following is a specification.

This invention relates to inclosures for porches, solariums, one of its objects being 10 to provide a structure which can be set up readily and which has a novel arrangement of screens, doors and windows whereby it is adapted for use at all times of the year.

Another object is to so arrange the parts 15 of the inclosure that practically all portions of the walls thereof will admit light no matter to what positions the wall panels may be adjusted to adapt the device for use under different climatic conditions.

20 A further object is to provide a structure of this character which is inexpensive and can be set up readily.

With the foregoing and other objects in view which will appear as the description 25 proceeds, the invention consists of certain novel details of construction and combinations of parts which will be hereinafter more fully described and pointed out in the claims, it being understood that various 30 changes may be made in the construction and arrangement of the parts without departing from the spirit or sacrificing any of the advantages of the invention as set forth in the appended claims.

35 In the accompanying drawings the preferred form of the invention has been shown.

In said drawings

Figure 1 is a front elevation of the inclosure.

40 Fig. 2 is a horizontal section therethrough.

Referring to the figures by characters of reference, 1 designates sills on which are mounted corner posts 2 and end posts 3, the latter being attached to the wall of the 45 building B from which extends the porch P on which the inclosure is mounted. The posts may be connected to the roof of the porch in any manner desired and in Fig. 1 beams 4 have been shown secured thereon.

50 Intermediate posts 5 are arranged between the posts 2 and between posts 2 and 3, there being preferably a pair of these intermediate posts at each side of the inclosure. The distance between the posts 5 of each pair is 55 slightly less than the distance between said

posts and the posts 2 and 3. Mounted between the upper end portions of all of the posts are rollers 6 on which are mounted shades 7 housed entirely in the spaces between the posts. 60

Secured to the outer faces of the posts 5 of each pair is a frame 8 which can be partly or entirely filled with glass so as to permit light to pass freely into the inclosure. These frames are fixedly mounted and 65 form the middle portions of the walls of the inclosure.

Hingedly connected, as at 9, to each side of each of the frames 8, is a frame 10 similar to the frames 8 and of such size as to 70 fill the space between said frame and the adjacent post 2 or 3. Two of these frames 10 with one frame 8 form each wall of the inclosure and one of these two frames is closed with glass G while the other one of 75 said frames carries a screen fabric S.

Hingedly connected as at 11 to each of the posts 5 at the inner side thereof is a frame 12 and these frames are adapted to extend into and close the spaces between 80 the inner portions of the posts 2 and 5 and between the inner portions of the posts 5 and 3. Those frames 12 adapted to be seated in the same spaces with the frames 10 carrying the glass G, are provided with 85 screen fabric S while those frames 12 adapted to be extended into the same spaces with the screen carrying frames 10 are provided with glass as shown at G.

The parts are so proportioned that when 90 it is desired to provide an inclosure which is screened, the glass holding frames 10 are swung out and back against the frames 8, thus to leave the screen carrying frames 12 as the sole closures of the spaces occupied 95 thereby. The glass carrying frames 12 are then swung inwardly against the posts 5 so as to leave the screen carrying frames 10 as the sole closures of the spaces occupied thereby. Thus each wall will be left 100 with two screened openings and with a central portion formed of three glass holding frames 8, 10 and 12. By swinging the glass carrying frames back to their closing positions and swinging the screen frames 10 onto the outer faces of frames 8 and the screen carrying frames 12 against the inner sides of the posts 5, the structure will be 105 glass inclosed. Any one of the frames 10 and 12 when in closing position can be used 110

as a door and all of the hinged frames are provided with suitable fastenings, indicated generally at 13.

What is claimed is:—

5. 1. An inclosure for porches, etc., including corner and end posts, intermediate posts arranged in pairs, frames fixedly connected to the intermediate posts of the respective pairs and closing the spaces therebetween, 10 hinged frames connected to the sides of each of the fixed frames and either one of which is adapted to swing to position either against the outer face of the fixed frame or across the space between the adjacent intermediate and corner or end posts, and hinged frames connected to the inner sides of the intermediate posts either one of which is adapted to swing to position across the space between said intermediate posts or across 15 20 the space between the adjacent intermediate and end or corner posts.
2. An inclosure for porches, etc., including corner and end posts, intermediate posts arranged in pairs, frames fixedly connected to the intermediate posts of the respective pairs and having glass therein for closing 25

Copies of this patent may be obtained for five cents each, by addressing the "Commissioner of Patents, Washington, D. C."

the spaces therebetween, an outer pair of hinged frames connected to the sides of each of the fixed frames and either one of which is adapted to swing to position either 30 against the outer face of the fixed frame or across the space between the adjacent intermediate and corner or end posts, and an inner pair of hinged frames connected to the inner sides of the intermediate posts, 35 either one of which is adapted to swing to position across the space between said intermediate posts or across the space between the adjacent intermediate and end or corner posts, one frame of each hinged pair being 40 closed with glass and the other frame of each hinged pair being screened, each glass carrying hinged frame being normally located in the space with a screened frame of the opposed pair.

In testimony that I claim the foregoing as my own, I have hereto affixed my signature in the presence of two witnesses.

JOHN OSCAR WEISSE.
